UNITED STATES PATENT OFFICE.

EDWARD B. WESTON, OF DAYTON, OHIO.

PAPER PAIL.

SPECIFICATION forming part of Letters Patent No. 723,565, dated March 24, 1903.

Application filed January 22, 1902. Serial No. 90,738. (No model.)

To all whom it may concern:

Be it known that I, EDWARD B. WESTON, a citizen of the United States, residing at Dayton, in the county of Montgomery and State 5 of Ohio, have invented certain new and useful Improvements in Paper Pails, of which the following is a full, clear, and exact description, reference being had to the accompanying drawings, forming part of this specification.

My invention relates to oyster-pails designed for liquids, oysters, berries, ice-cream, and the like.

The special object of my invention is to provide a novel lock for the outside top covers of the pail, whereby the top covers may be locked shut by merely pressing the covers together.

Heretofore it has been usual to attach a tin 20 loop at one side edge of the top cover and to attach a tin strip or tongue to the other side edge, and in order to lock the top after pressing the top covers together it has been necessary to thread the tongue through the loop 25 and after drawing it tight to bend the tongue over to lock the top. It is quite difficult at times to thread this tongue in the hole or loop on the opposite side, and even then it is necessary to take hold of the end of the tongue 30 after threading it through the loop to bend it over, thus involving a series of operations frequently difficult, especially if the fingers of the operator, as frequently happens, are numb with cold. It is the purpose of my invention to substitute for this ordinary form 35 of lock a certain novel construction to be hereinafter particularly pointed out and claimed, whereby the covers may be locked by simply pressing them together.

40 A second feature of my invention consists in so forming the blank and folding same that stiff interlocking flaps may be provided to form a tight and close fitting top for the pail to prevent the contents from spilling out.

45 In the drawings, Figure 1 is a plan view of the blank from which my improved pail is formed. Fig. 2 is a perspective view of the pail partly closed and ready for locking. Fig. 3 is a central vertical section of the pail with 50 the top covers open, ready to receive the con-

tents. Fig. 4 is a similar section with the inner top covers closed.

The blanks are cut and scored from sheets of suitable stiff paper, as shown in Fig. 1, in which, by the score-lines, A forms the bottom, 55 B the sides, C C the ends, with corner folds D E D E and F G F G between the sides and ends. For reinforcing the top covers corner-fold extensions H I are provided for the corner folds D E and F G, while attached 60 to the ends C C and between the adjacent corner-fold extensions I I are the top covers L M. These top covers L M are of sufficient length to overlap when folded, as hereinafter described, and they are cut away from the 65 corner-fold extensions I I at points a a and b b.

N P are extensions of the sides which form the external top covers and are provided with a locking device, as hereinafter described, and to permit folding in of the top covers they are 70 provided with the diagonal score-lines c c d d.

Attached to the top cover P is the tin strip e, provided with an opening f to form a loop, and attached to the other top cover N is the tin strip g, having a permanent hook h formed 75 thereon.

In folding the pail the side and end walls are brought into upright position, and the corner folds between the sides and ends are folded together and outside of the ends C C. 80 The corner-fold extensions H I then form a quadruple thickness for the end top covers, with the end extensions L M on the inside and detached at the points a b from the corner-fold extensions. These parts are then 85 secured together by the wire loops l l, and the wire bail R is then secured through the corner folds and ends and bent over on the inside to fasten same.

To close the pail, the top covers L M are 90 pushed in and caused to overlap, as shown in Fig. 4, forming a stiff and close fitting cover for the contents. This folding in of the top covers L M causes the side extensions N P to fold on the score-lines c c d d, and then the 95 outside covers are pressed down and the sides pushed slightly together, which brings the hooks h underneath the opening f in the strip e. When released, the pail expands, forcing the loop under the hook, forming an auto- 100

matic and at the same time perfectly safe and tight lock.

Having thus described my invention, what I claim, and desire to secure by Letters Patent, is—

A paper pail, made from a single blank of paper, scored and creased to form bottom, sides and ends, with corner folds between the sides and ends, end and side extensions to form the top covers, with corner-fold extensions between the end and side extensions, said corner folds being folded back to over-

lap the ends with the corner-fold extensions overlapping to form a quadruple reinforcement for the top, and the end extensions being partly severed from the corner-fold extensions to form overlapping top covers thus reinforced, substantially as shown and described. 15

EDWARD B. WESTON.
